UNITED STATES PATENT OFFICE.

WILLIAM LOWE, OF BRIDGEPORT, CONNECTICUT.

SYSTEM OF TRAVELING TRANSFER-CRANES.

SPECIFICATION forming part of Letters Patent No. 310,449, dated January 6, 1885.

Application filed November 10, 1884. (No model.)

To all whom it may concern:

Be it known that I, WILLIAM LOWE, a citizen of the United States, residing at Bridgeport, in the county of Fairfield and State of Connecticut, have invented certain new and useful Improvements in System of Traveling Transfer-Cranes; and I do hereby declare the following to be a full, clear, and exact description of the invention, such as will enable others skilled in the art to which it appertains to make and use the same.

My invention has for its object to devise a system of traveling cranes which shall be simple in construction and economical in cost, and which shall be so constructed and arranged that trolleys, carriages, or traveling blocks may be transferred from one crane to another, or to stationary tramways, or from stationary tramways to a crane without depositing the load, without loss of time, and without the use of greater power than is required to move a trolley or carriage upon a tramway.

Heretofore traveling cranes have been used that spanned an entire workshop; also, stationary and walking swinging cranes with trolleys or carriages traveling upon their arms. Both of these systems, however, permit the handling of but one load at a time within the space covered, and in case the load is to be transferred it must be carried to the limit of one crane, deposited, and released by that crane before it can be picked up by another crane or a carriage upon a tramway. Both systems, moreover, are expensive to construct. Still another system of moving heavy weights is to erect a system of overhead tracks or tramways, and provides switches by means of which a traveling carriage may be transferred from one track to another. This system also is objectionable on account of its greater first cost.

With this system transfers from one track to another can only be made by manipulation of switches, and it is impossible without a perfect net-work of tracks and switches to take up, and, above all to deposit, the load at any particular place that may be desired.

In order to obviate the objections to the various systems now in use, I have devised the simple and novel system of transfer-cranes which I will now describe, referring by letters to the accompanying drawings, forming part of this specification, in which—

Figure 1 is a front elevation of a crane in position to transfer the trolley to a stationary tramway. Fig. 2 is a front elevation of two cranes placed side by side and locked together, so that the trolley may be transferred from one crane to the other; and Fig. 3, a cross-section on the line $x-x$ in Fig. 2, with one of the supporting-beams and the trolley in elevation.

Similar letters indicate the same parts in all the figures.

A indicates supporting-beams, which may be suspended, attached to columns, or secured in any suitable manner; and B, tracks upon which cranes C run. C¹ are the crane-wheels, rigidly secured to a shaft, C², upon which is a wheel, C³, over which a chain, D, passes, by which the crane is moved in either direction upon the track. These parts are all of ordinary construction and form no part of my present invention.

C⁴ represents tracks carried by or forming part of the cranes. These tracks are preferably placed transversely to the line of movement of the cranes, and are all arranged upon the same horizontal plane, so that when brought into line they will register with each other.

E represents stationary tracks or tramways, which lie in the same horizontal plane as tracks C⁴, and register therewith when brought into line.

F is a trolley, carriage, or traveling block adapted to run upon tracks C⁴ and E.

G is the ordinary chain by which the trolley is moved along upon the tracks, and H the usual lifting-chain.

Any number of trolleys, carriages, or blocks may be used, the construction of which forms no part of my present invention.

I represents bolts which slide in ways K, by which the cranes may be locked together; or a crane may be locked in such position that the trolley may readily pass from one of the crane-tracks C⁴ to another crane-track, or to a stationary track, E, or vice versa.

It should be understood that I do not limit myself to the specific construction shown, as the shape and general arrangement of the parts may be greatly varied without departing from the spirit of my invention, the gist of which lies in the broad idea of a series of simple and inexpensive traveling cranes, or

cranes and stationary tramways, so constructed that the trolleys or carriages may be passed from one crane or tramway to another crane or tramway without depositing the load and 5 without loss of time. The cranes all run independently of each other; but when locked together two or more cranes may be operated as one crane.

The system may be operated equally well 10 by hand or by power.

The cheapness and ease of management of this system, together with the fact that more than one load may be handled at a time within 15 the space covered by the system, make it especially adapted to the requirements of machine-shops, foundries, mills, warehouses, &c.

I claim—

1. The combination, substantially as before set forth, of two or more traveling cranes carrying tracks arranged in the same horizontal 20 plane, and trolleys or carriages which are adapted to travel on said tracks.

2. The combination, substantially as before set forth, of two or more traveling cranes carrying tracks arranged transversely to the line 25 of movement of the cranes, means—for example, bolts—for locking the cranes together when the tracks register, and trolleys or carriages adapted to travel on said tracks and pass freely from one crane to another. 30

3. The combination of traveling cranes carrying tracks, which register with each other, stationary tracks or tramways, which register with those upon the cranes, and trolleys or carriages adapted to travel on said tracks and 35 pass freely from one track to another without depositing the load.

In testimony whereof I affix my signature in presence of two witnesses.

WILLIAM LOWE.
